UNITED STATES PATENT OFFICE.

J. ARTHUR ADAMSON, OF PHILADELPHIA, PENNSYLVANIA.

SUSPENDERS.

SPECIFICATION forming part of Letters Patent No. 279,306, dated June 12, 1883.

Application filed January 9, 1882. (No model.)

To all whom it may concern:

Be it known that I, J. ARTHUR ADAMSON, a citizen of the United States, residing in Philadelphia, Pennsylvania, have invented certain 5 Improvements in Suspenders, of which the following is a specification.

My invention relates to an improvement in waist straps or ends for suspenders, the object of the improvement being to effect the secure 10 attachment of the cord to the flat tapes forming the button-loops.

In the accompanying drawings, Figure 1 is 15 a view of a waist strap or end for suspenders of the character to which my invention relates; Fig. 2, a transverse section on the line 12, drawn to an enlarged scale; Fig. 3, a transverse section on the line 34, also enlarged; Figs. 4 and 5, enlarged views of the clasp, forming the main 20 feature of my invention; and Fig. 6, a view of the blank from which the clasp is made.

The waist strap or end, to which my invention relates, comprises the cord A, the button-loops B B, of flat braid, and the clasps D-D, whereby the button-loops and the cord are 25 secured together. The cord A may be secured to the main web of the suspenders in any of the usual ways, this forming no part of my invention, the latter being devoted to the construction of the clasps D, each of which, as 30 shown in Figs. 2 to 6, comprises a back plate, a, and opposite wings b b, the plate and wings being shaped and bent so as to embrace the cord A and the overlapping ends of the braid-loops B. In that portion of the clasp which 35 embraces the cord A incisions are made in the plate a, and the metal is struck up so as to form teeth d, another tooth, d, being also formed on the end of this portion of the plate, the opposite end of the plate—that is to say, the portion which aids in confining the overlapping 40

ends of the braid forming the loops B—having similar teeth, e. (See Figs. 4, 5, and 6.) Each of the wings b of the clasp has upon its edge teeth f, so that when the clasp is applied to the cord and loops, as shown in Figs. 1, 2, and 45 3, the teeth e penetrate the braid from the back and the teeth f penetrate said braid from the front, so that a much firmer hold upon the braid is insured than when the teeth e alone are used on this portion of the clasp. The 50 teeth f are nearer the center of the braid than the teeth e, so that both sets of teeth have a firm hold on the braid, and in addition to this secure hold the end teeth, d and e, being arranged transversely or across the line of strain⁵⁵ upon the cord and braid, serve to effectually resist any sudden or severe strain, and prevent it from being transmitted with full force to the longitudinal teeth d, e, and f.

I claim as my invention—

1. The combination of the cord A and braid-loops B of a suspender-end with clasps D, having teeth d and e struck up from the body, and other teeth, f, formed on the bent wings b of the clasp, said wings e and f acting upon different 65 portions of the braid forming the loops, as set forth.

2. The combination of the cord A and braid-loops B of a suspender-end with clasps D, having longitudinal teeth d, e, and f in the body 70 and on the side wings and transverse teeth d and e at the ends, as set forth.

In testimony whereof I have signed my name to this specification in the presence of two subscribing witnesses.

J. ARTHUR ADAMSON.
